UNITED STATES PATENT OFFICE.

HERBERT C. STOCKWELL, OF LOS ANGELES, CALIFORNIA, ASSIGNOR TO
THE YALE & TOWNE MANUFACTURING COMPANY, OF STAMFORD,
CONNECTICUT.

AUTOMATIC BOLT-OPERATING DEVICE.

SPECIFICATION forming part of Letters Patent No. 645,431, dated March 13, 1900.

Application filed August 31, 1894. Serial No. 521,867. (No model.)

To all whom it may concern:

Be it known that I, HERBERT C. STOCKWELL, a citizen of the United States, residing at Los Angeles, in the county of Los Angeles and State of California, have invented certain new and useful Improvements in Automatic Bolt-Operating Devices, of which the following is a specification.

My invention relates to that class of bolt-operating mechanisms which employ casting and retracting powers controlled, respectively, by the act of closing the door and by a suitable time mechanism and which employ a normal or primary retracting power and an auxiliary or reserve retracting power. Bolt-operating mechanisms of this class have been heretofore made with two retracting powers, either or both of which may be used to retract the bolts, and in some cases devices have been constructed for disconnecting one from the other; but all previous devices have been somewhat complicated, so that in practice it has been more usual to so construct the devices that in case either retracting power should fail to work the other would be obliged to compress the casting-springs of the side not working in order to retract the bolts. While devices thus made work practically and with general satisfaction, it is obviously better that the retracting power should not be required to be so strong as to be able to retract the bolts and at the same time to compress any casting-springs, because when working normally and not compressing the casting-springs an unnecessary force is exerted upon the bolts. My present invention relates, therefore, to certain novel features of construction; to be hereinafter fully described, and particularly pointed out in the claims, for disconnecting the casting power in those cases where the reserve power is brought into use, so that said reserve power in retracting the boltwork is not called upon to compress the casting-springs, but acts upon the bolts with entire independence; and my device has the further advantage that when the reserve power has been called into action the bolts cannot be again thrown forward unless the reserve power is set, so that it is impossible to lock a safe or other receptacle un-

less both the primary and reserve powers are in operative condition.

In the accompanying drawings, Figure 1 is a plan of one side of the device, the cover being removed to disclose the usual form of detent mechanisms which control the respective retracting powers and are themselves adapted to be controlled by a time mechanism. Fig. 2 is a plan of the opposite side of the device with the cover removed, showing the casting power, the normally-operating retracting power, and the emergency or auxiliary retracting power, together with means for removing the obstruction offered by the casting power to either retracting power in the operation of unlocking, the parts being shown in the locked position. Fig. 2^a is a section on the line *x* *x*, Fig. 2. Fig. 3 is a view similar to Fig. 2, but showing the parts in the positions of normal unlocking. Fig. 4 is a similar view showing the parts in the positions of the emergency unlocking—that is to say, when the normally-operating retracting power has failed to do its duty and the unlocking has been accomplished by the reserve power.

Referring to Fig. 1, which shows the detent mechanisms, 1 and 1^a are a pair of shafts mounted transversely in the casing A of the device to control the respective unlocking powers, and these shafts are provided with the usual levers *a* *a'*, by which the shafts are prevented from turning until released by the time-lock. These levers *a* and *a'* have the usual hooked ends engaged by the correspondingly-hooked short arms of levers *b* and *b'*, pivoted at *c* and *c'* and controlled by levers *d* and *d'*, pivoted at *e* and *e'* and connected to the ends of levers *b* *b'* through the medium of slots *ff'* and pins *gg'*. The levers *d* *d'* are provided at their outer ends with pins *h* *h'* for engagement by detents *i* *i'*. The detent *i* is so located that its end *k* projects outside of the casing and is thus adapted to be tripped by any suitable time mechanism. This tripping is communicated to the other detent *i'* through the medium of a pivoted yoke L. This yoke L is so constructed and arranged with reference to the detent *i* that when said detent is moved by the time-lock 100

for unlocking the hook releases the levers of the primary unlocking power before it impinges against said yoke. Thus the bolts are normally operated by the primary unlocking power alone, and usually a dog comes into action by the unlocking of the bolts, so that the reserve power does not act except in case of emergency; but if for any cause the primary unlocking power does not retract the bolts then continued motion of the hook *i* under the impulse of the time-lock causes it to act upon the pivoted yoke *L* and this in turn to unlatch the reserve detent *i'*, and thus bring the reserve unlocking power into action.

Referring to Figs. 2, 3, and 4, which illustrate my invention, together with the mode of operation and the construction and relative arrangement of parts, it will be seen that the shafts 1 and 1^a are provided on their ends opposite the detent-levers *a* and *a'* with short levers 2 and 2^a, and these levers 2 and 2^a are connected, through the medium of links 3, with the sliding carriages 4 and 4^a of the primary and reserve bolt-retracting powers 5 5^a. The retracting powers which operate upon the carriages 4 and 4^a consist of two groups of springs of four each, as shown. The said carriages in order to retract the bolts for unlocking the safe are connected, through draw-bars 6 and 6^a, with the attaching-plate *B*, which is arranged for attachment to the bolt-work in the usual manner. These retracting powers are arranged for independent operation, and in order that either may exert its influence upon the plate *B*, which is attached to the bolts, and at the same time to prevent the possibility of either opposing the other in the event of its becoming disabled the draw-bars 6 and 6^a are connected to the plate *B* by means of the heads 7 on said bars and the flange 9 on the plate, through which latter the draw-bars work and with which they engage by their heads 7. The plate *B* has slots or recesses 8 in order that both draw-bars may be thrust forward when the retracting powers are being set without projecting the bolts and also to permit either retracting power in operating upon the bolts to draw the plate *B* backward without obstruction from the other draw-bar in the event of its power becoming disabled or blocked.

10 represents the casting power, which exerts its force upon the bolts to project them into locked position through the medium of a front movable carriage 11, which abuts against the flange 9 of the plate *B*. This casting power has bearing at the rear against the normally-stationary push-block 12.

From so much of the description it will be observed that the device has a single casting power, with working connections with the bolts or a plate to be attached thereto, and two independently-operative retracting powers having independent detents for opposing their operation until the detents shall have been released by a time mechanism.

The push-block 12, against which the cast-

ing-springs 10 abut, is supported by the carriage 4 of the primary retracting-springs, so that when the bolts are retracted by the primary unlocking power 5 the carriage 4 travels backward with said push-block 12 and the casting-springs go with them bodily, so that no obstruction occurs to the retraction of the boltwork; but the reserve unlocking-springs 5^a are carried by another carriage 4^a, which is not directly connected with the casting-springs, so that if said casting-springs are not carried out of the way by the primary unlocking-springs the reserve unlocking-springs in order to retract the bolts would be obliged to compress said locking-springs. To avoid this objectionable feature, I provide in such case for removing the support of the push-block 12 from the primary retracting-carriage, so that said push-block 12 and the locking-springs will be free to move backward, and therefore the compressing of the casting-springs is also avoided during the retracting of the bolts by the reserve power. To thus remove the support of push-block 12, I make said support of a bell-crank lever 12^a, the lower arm of which acts as a brace for the rear of the push-block 12 and normally rests against the stump 13^a, which is attached to a projection 13^b on the primary carriage 4, while its upper or vertical arm 12^c rests against the rear of the reserve-carriage 4^a. Now assuming that the primary unlocking power has failed to work and the reserve unlocking power is brought into action, obviously the first movement of the reserve-carriage backward will be to throw the bell-crank lever 12^a out of engagement with the stump 13^a. This will disconnect the push-block 12 of the casting-springs, so that the block will be moved backward by its springs instead of compressing them, and the bolts will be retracted without compressing said casting-springs. The lever 12^a is pivoted to push-block 12 at 12^b and is held normally in engagement with lug 13^a by means of the spring 12^d bearing upon short arm 12^e of said lever. When this takes place, the parts will occupy the positions shown in Fig. 4.

In addition to the effect produced by the means which I have described for displacing the connection of the push-block 12 a special advantage exists in the use of this construction in that after the emergency unlocking power has operated it will be necessary to set the same and force the carriage 4^a forward, and thus release the lever-arm 12^c from said carriage 4^a before the locking power can be set up. Moreover, the primary power-carriage by the nature of the construction by its forward movement in resetting causes the supporting bell-crank lever of the push-block to assume its proper position. It is therefore obvious that the apparatus cannot be set for use except in the proper way nor without all parts assuming their proper relations.

In order to reset the springs of the retracting powers, the shafts 1 and 1^a are rotated by

means of the usual tool applied to the heads of levers a and a' . (Shown in Fig. 1.) This rotation of the shafts 1 and 1^a forces the carriages 4 and 4^a forward through the medium 5 of the levers 2 and 2^a and links 3, compressing the springs 5 and 5^a until the levers 2 and 2^a come against the stops y . (See Fig. 2.) As the levers 2 and 2^a are intercepted by these stops the levers a and a' on the opposite ends 10 of the shafts 1 and 1^a will have caused the levers b and b' and detents i and i' to assume the proper relations to lock the shafts 1 and 1^a against retrograde rotation and to hold them securely in opposition to the retracting powers 5 and 5^a until the detent i is tripped by the time 15 mechanism in the well-known manner.

Having thus described my invention, what I claim as new, and desire to secure by Letters Patent, is—

20 1. In a bolt-operating device, the combination of a casting power, a primary retracting power, a stump carried thereby, a lever connected to the casting power and adapted to engage the stump for holding the casting power to its work, an auxiliary retracting power, and an arm 12° connected to said le- 25

ver and supported in the path of the auxiliary retracting power and adapted to be moved thereby for disconnecting the casting power when the boltwork is retracted, substantially as described. 30

2. In a bolt-operating device; the combination of the casting power consisting of suitable springs; the front and rear carriages upon which said springs operate; a lever on 35 the rear carriage; a primary retracting device having a stump normally engaged by the lever and through it holding the casting power to its work; the laterally-projecting arm connected to the lever and adapted to throw it 40 out of engagement with the stump; and an auxiliary or reserve retracting power operating independently of the primary retracting power and located to engage laterally-projecting arm in the movement of retraction, substantially as and for the purpose set forth. 45
